United States Patent Office.

HENRY D. BLAKE, OF NEW BRITAIN, CONNECTICUT, ASSIGNOR TO P. AND F. CORBIN, OF SAME PLACE.

Letters Patent No. 75,663, dated March 17, 1868.

IMPROVED MACHINE FOR RIVETING HINGES.

The Schedule referred to in these Letters Patent and making part of the same.

TO ALL WHOM IT MAY CONCERN:

Be it known that I, HENRY D. BLAKE, of New Britain, in the State of Connecticut, have invented, made, and applied to use a certain new and useful Improvement in Riveting-Machines; and I do hereby declare the following to be a full, clear, and exact description of the said invention, reference being had to the annexed drawing, making part of this specification, wherein—

Figure 1 is a plan of my said machine.

Figure 2 is a vertical section at the line $z z$.

Figure 3 is an end view, and

Figure 4 a side view of the riveting-die; and

Figure 5 is a side view of a portion of a hinge, showing the rivet-head at one end of the wire or pin.

Similar marks of reference denote the same parts.

Heretofore it has been usual to rivet up the pins of hinges by a hammer, the concussion of which is likely to bend the pin, causing the same to bind and the hinge to work stiff.

My invention is especially adapted to the riveting of hinges, but may be applied to any other character of rivet in which the heads can be formed at the two ends of the wire or rod simultaneously; and said invention consists in spreading the metal to form the rivet-heads by the revolution of a die or spreader acting under pressure, to gradually extend the metal and form the head with a rounded and smooth surface.

This improvement in riveting may be used for the pins of butt or strap-hinges.

In the drawing, a is a bed, upon which are boxes carrying the main driving-shaft b , on which are the pulleys c d , and gear-wheel e . f is a shaft supported in a movable head, g , and rotated by a cross-belt from the pulley c . The head g is supported by the bed a , and is provided with a screw-clamp below the slotted bed, to allow the head to be adjusted nearer to or further from the mandrel-head h to accommodate the length of rivet to be operated upon, and the head h may also be similarly adjusted. The head h carries a mandrel or shaft, i , and at its end, and the end of the shaft f facing it, are dies k k , that form the rivet-heads, and are more particularly described hereafter. The shaft i is provided with a pulley, l , and belt to the pulley d , and m is a spring and sliding fork taking a neck in the shaft i , and keeping it against the slide n , that is fitted to move endwise in the boxes 2 2 , on h , by a lever, o , on a fulcrum 3 , acted upon by a cam, p , on the shaft q , that is driven by the wheel r to the gear e .

It will now be understood that the shafts f and i are revolved in opposite directions, that they carry at their ends riveting-dies, that one of the shafts is moved endwise as it revolves, and that the parts are to be so adjusted that the distance between the dies k k , at the termination of each movement, corresponds to the length of the riveted wire.

The riveting is effected by the rotation, in opposite directions, of the dies that act by pressure at the ends of the wire, rod, or rivet-blank, to spread, extend, and smooth the metal without bending the wire or rod.

The red lines in fig. 3 represent the size of the wire, and of the head within the die.

The position of the cam p is adjustable by set-screws, so that the movement of the dies endwise can be accurately determined.

What I claim, and desire to secure by Letters Patent, is—

A riveting-tool composed of a rod of metal having V-shaped grooves crossing and radiating from its longitudinal axis across a face or end surface which is otherwise perpendicular to the axis of said rod, substantially as described.

I also claim the riveting-tool set forth in the foregoing claim, in combination with mechanism for operating the same, arranged substantially as described.

In witness whereof, I have hereunto set my signature, this 3d day of October, A. D. 1867.

HENRY D. BLAKE.
